UNITED STATES PATENT OFFICE.

LUTHER L. KNOX, OF AVALON, PENNSYLVANIA, ASSIGNEE TO KNOX PRERESSED & WELDED STEEL COMPANY, OF PITTSBURGH, PENNSYLVANIA, A CORPORATION OF PENNSYLVANIA.

WATER-COOLED VALVE.

1,151,193.

Specification of Letters Patent. Patented Aug. 24, 1915.

Application filed December 24, 1913. Serial No. 603,582.

To all whom it may concern:

Be it known that I, LUTHER L. KNOX, a citizen of the United States, residing at Avalon, in the county of Allegheny and State of Pennsylvania, have invented a new and useful Improvement in Water-Cooled Valves, of which the following is a full, clear, and exact description, reference being had to the accompanying drawings, forming part of this specification, in which—

Figure 1 is a longitudinal vertical section showing one form of my improved valve in closed position; Fig. 2 is a front elevation of the same partly broken away; Fig. 3 is a perspective detail view of the water-cooled seat; Fig. 4 is a similar view of the valve; Fig. 5 is a perspective view of the cover plate; and Fig. 6 is a similar view of the sliding shutter co-acting with the cover plate.

My invention relates to the class of water-cooled valves controlling passages through which hot gases pass. Water-sealed valves for such purposes are objectionable in exposing the gases to direct contact with water, and also in requiring tortuous passages in order to properly supply the valve, thus giving added friction. Water-cooled valves have been troublesome on account of improper seating, leakage of gas, etc. My invention is designed to overcome these difficulties, and to provide a water-cooled valve which is so arranged that its own weight will hold it in proper closed position, and will seat it even though worn; while at the same time retaining the gate valve principle which does away with the need for tortuous flues which require greater draft.

In the drawings in which I show the preferable form of my invention, 2 represents a hot blast conduit having a transverse opening 3 therein, one side of which extends at an angle to the vertical. On this inclined plane surface is set the water-cooled valve seat 4, preferably of the type shown in Fig. 3. As here shown the seat consists of a rectangular frame having hollow side-guiding projecting portions, 5, 5. Water is circulated through this seat by any suitable connections. In the form shown, the water is fed to the bottom through supply pipes 6, and taken off at the top through the outlet pipe 7. These pipes of course extend to any suitable piping to receive and conduct away the water which circulates continuously

through the seat. With this seat coats the valve 8, shown in Fig. 4, which is hollow, and one face of which is flat to fit the coacting surface of the seat. The other face is preferably provided with an offset portion 9 to receive the water supply pipes 10, the water being taken off from the top through pipes 11. The pipes 10 and 11 also preferably serve as valve operating connections and are extended upwardly within a casing 12 and through a cover plate 13, closing its top. This cover plate 13 is preferably reinforced with angles or stiffeners 14, and is provided with longitudinal slots 15 through which the pipes 10 and 11 extend. With these slots coat sliding shutters 16, shown in Fig. 6, having holes through which the pipes extend, these shutters sliding along the cover plate as the valve is raised and lowered.

Above the cover plate 13 a bar or frame 17 is secured to the pipes, and to this frame is connected the operating cable 18, shown as extending over a pulley 19 to a suitable operating point. The cable is so connected that as it lifts the valve, it also pulls it side-wise toward the seat, so that the valve slides along the seat for a certain distance before it rises therefrom in opening the flue. Similarly, in closing the valve, as the valve descends it contacts with the seat before closing the flue and then slides down the seat between the guides 5 in reaching its final closed position. When lifted, the valve is contained within the casing 12, the hot gases then flowing through the window or hole in the seat.

The advantages of my invention result from the use of the gate-type of valve, in which the valve is held to its seat by gravity or its own weight. Also from the automatic adjustment of the valve and its seat on account of the weight holding it closed. Any wear or irregularity is thus taken up and the valve will effectually close the passage owing to its weight holding it on its seat, although it moves transversely in a general vertical direction across the horizontally extending flue. No water is exposed to the gases, as is the case where open sealing troughs are employed and the difficulties heretofore present in water-cooled valves are reduced or done away with.

The valve may be used with any hot blast passage whether for reversing the flow of

gases through regenerative furnaces, or in any other connection. The valve and valve seat may be made without water-cooling passages as in many cases iron or castings will sufficiently resist the heat, the weight of the valve holding it closed and causing it to fit against the seat.

Many changes may be made in the form of valve, its seat, and the operating mechanism without departing from my invention.

I claim:

1. The combination of an inclined valve seat arranged transversely of a conduit, a valve adapted to seat by gravity in an inclined position on said seat, and actuating connections for the valve, said connections having means whereby the valve is drawn backwardly against the seat during a portion of its lifting movement and is then lifted in a substantially vertical direction for the remainder of its movement; substantially as described.

2. The combination with an inclined valve seat arranged transversely of a conduit, of a valve of the gate type arranged to rest by gravity in an inclined position on said seat, and an actuating connection for said valve, said actuating connection having a flexible member whose point of support is slightly to one side of the center of gravity of the valve, whereby said valve is drawn backwardly against its seat during a portion of its lifting movement, and is then raised in a substantially vertical direction during the remainder of its movement; substantially as described.

3. The combination with a valve-seating member having an inclined seating face, of a hollow water-cooled valve arranged to rest in an inclined position against said face, spaced water-circulating pipes connected exteriorly to the upper and lower portions of said valve and communicating with the interior thereof, and actuating means connected to said pipes, substantially as described.

4. The combination with an inclined valve seat, of a hollow water-cooled valve arranged to rest in an inclined position against said seat, having water circulating pipes rigidly connected to the upper and lower portions of said valve, together with actuating means attached to said pipes, said actuating means being arranged to cause the valve to

swing backwardly by gravity against said seat during at least a portion of its raising movement; substantially as described.

5. The combination with a hot-blast conduit pipe having a transverse opening, an inclined water-cooled seat surrounding said opening, a hollow water-cooled valve adapted to rest by gravity in an inclined position against the inclined surface of the seat, a casing above the valve and communicating with the conduit, a slotted cover for said casing, lifting members attached to the valve and extending upwardly through the casing and through said slots, and means for closing the slots around said lifting members; substantially as described.

6. A water-cooled hot-blast valve of the gate type adapted to rest in an inclined position against its seat, a casing for said valve having a slotted cover plate, lifting members connected to said valve and extending upwardly through the slots of the cover plate, actuating means connected to the lifting members above the cover plate, said actuating means being arranged to first move the valve backwardly against its seat and then to raise it vertically, and movable cover members for the said slots to permit the necessary movement of said lifting members in the slots; substantially as described.

7. The combination with an inclined valve seating member, of a valve arranged to rest in an inclined position against an inclined seating face of said member, and lifting means for said valve, said lifting means and valve being arranged to move laterally toward and away from the inclined seating face of said seat as the valve is raised and lowered; substantially as described.

8. A water-cooled hot blast valve of the gate type, adapted to rest in an inclined position against its seat, the casing having a slotted cover plate, water pipes extending to the valve through slots in the cover plate, means for closing said slots, and a connection arranged to lift the pipes and move them sidewise; substantially as described.

In testimony whereof, I have hereunto set my hand.

LUTHER L. KNOX.
